(57) **CLAIM**

The ornamental design for a footrest assembly and footrest support member for a reclining furniture item, as shown and described.

DESCRIPTION

FIG. 1 is a perspective view of a first embodiment of the present invention.

FIG. 2 is a top view thereof;

FIG. 3 is a bottom view thereof;

FIG. 4 is a right side elevational view thereof, the left side elevational view being a mirror image thereof;

FIG. 5 is a front elevational view thereof;

FIG. 6 is a rear elevational view thereof;

FIG. 7 is a perspective view of a second embodiment of the present invention;

FIG. 8 is a top view of FIG. 7;

FIG. 9 is a bottom view of FIG. 7;

FIG. 10 is a right side elevational view of FIG. 7, the left side elevational view being a mirror image thereof;

FIG. 11 is a front elevational view of FIG. 7;

FIG. 12 is a rear elevational view of FIG. 7;

FIG. 13 is a perspective view of a third embodiment of the present invention;

FIG. 14 is a top view of FIG. 13;

FIG. 15 is a bottom view of FIG. 13;

FIG. 16 is a right side elevational view of FIG. 13, the left side elevational view being a mirror image thereof;

FIG. 17 is a front elevational view of FIG. 13;

FIG. 18 is a rear elevational view of FIG. 13;

FIG. 19 is a perspective view of a fourth embodiment of the present invention;

FIG. 20 is a top view of FIG. 19;

FIG. 21 is a bottom view of FIG. 19;
FIG. 22 is a right side elevational view of FIG. 19, the left side elevational view being a mirror image thereof;
FIG. 23 is a front elevational view of FIG. 19;
FIG. 24 is a rear elevational view of FIG. 19;
FIG. 25 is a perspective view of a fifth embodiment of the present invention;
FIG. 26 is a top view of FIG. 25;
FIG. 27 is a bottom view of FIG. 25;
FIG. 28 is a right side elevational view of FIG. 25, the left side elevational view being a mirror image thereof;
FIG. 29 is a front elevational view of FIG. 25;
FIG. 30 is a rear elevational view of FIG. 25;
FIG. 31 is a perspective view of a sixth embodiment of the present invention;
FIG. 32 is a top view of FIG. 31;
FIG. 33 is a bottom view of FIG. 31;
FIG. 34 is a right side elevational view of FIG. 31, the left side elevational view being a mirror image thereof;
FIG. 35 is a front elevational view of FIG. 31;
FIG. 36 is a rear elevational view of FIG. 31;
FIG. 37 is a perspective view of a seventh embodiment of the present invention;
FIG. 38 is a top view of FIG. 37;
FIG. 39 is a bottom view of FIG. 37;
FIG. 40 is a right side elevational view of FIG. 37, the left side elevational view being a mirror image thereof;
FIG. 41 is a front elevational view of FIG. 37;
FIG. 42 is a rear elevational view of FIG. 37;
FIG. 43 is a perspective view of a eighth embodiment of the present invention;
FIG. 44 is a top view of FIG. 43;
FIG. 45 is a bottom view of FIG. 43;
FIG. 46 is a right side elevational view of FIG. 43, the left side elevational view being a mirror image thereof;
FIG. 47 is a front elevational view of FIG. 43;
FIG. 48 is a rear elevational view of FIG. 43;

FIG. 49 is a perspective view of a ninth embodiment of the present invention;
FIG. 50 is a top view of FIG. 49;
FIG. 51 is a bottom view of FIG. 49;
FIG. 52 is a right side elevational view of FIG. 49, the left side elevational view being a mirror image thereof;
FIG. 53 is a front elevational view of FIG. 49;
FIG. 54 is a rear elevational view of FIG. 49;
FIG. 55 is a perspective view of a tenth embodiment of the present invention;
FIG. 56 is a top view of FIG. 55;
FIG. 57 is a bottom view of FIG. 55;
FIG. 58 is a right side elevational view of FIG. 55, the left side elevational view being a mirror image thereof;
FIG. 59 is a front elevational view of FIG. 55;
FIG. 60 is a rear elevational view of FIG. 55;
FIG. 61 is a perspective view of eleventh embodiment of the present invention;
FIG. 62 is a top view of FIG. 61;
FIG. 63 is a bottom view of FIG. 61;
FIG. 64 is a right side elevational view of FIG. 61, the left side elevational view being a mirror image thereof;
FIG. 65 is a front elevational view of FIG. 61;
FIG. 66 is a rear elevational view of FIG. 61;
FIG. 67 is a perspective view of twelfth embodiment of the present invention;
FIG. 68 is a top view of FIG. 67;
FIG. 69 is a bottom view of FIG. 67;
FIG. 70 is a right side elevational view of FIG. 67, the left side elevational view being a mirror image thereof;
FIG. 71 is a front elevational view of FIG. 67; and,
FIG. 72 is a rear elevational view of FIG. 67.
The elements shown in broken lines are for environmental purposes and relate to elements which do not form part of the claimed invention.
